L. KAPLAN

REENFORCED HOSIERY AND METHOD OF PRODUCING SAME

Filed Aug. 25, 1927

FIG. 1.

FIG. 2.

FIG. 3.

FIG. 4.

Inventor:

Attorney

UNITED STATES PATENT OFFICE.

LOUIS KAPLAN, OF ASTORIA, NEW YORK.

REENFORCED HOSIERY AND METHOD OF PRODUCING SAME.

Application filed August 25, 1927. Serial No. 215,351.

The present invention relates to hosiery, and aims to provide novel means for reenforcing stockings, socks and other hosiery, such as at the toe and heel, so that holes will 5 not be worn or torn therein, thereby lengthening the life of the hosiery.

Another object is to provide an article of hosiery reenforced in a novel manner to resist wear and tear at the points where holes 10 usually occur.

A further object is the provision of a novel method of producing the reenforced hosiery, to facilitate manufacture.

With the foregoing and other objects in 15 view, which will be apparent as the invention is more fully understood, the invention resides in the features as hereinafter described and claimed, it being understood that changes may be made within the scope of what is 20 claimed, without departing from the spirit of the invention.

The invention is illustrated in the accompanying drawings, wherein—

Figure 1 is a side elevation of a stocking 25 showing the openings therein at the points where the stocking is to be reenforced.

Fig. 2 is an enlarged plan view of a portion of the stocking along one edge of one of the openings, showing the reenforcement.

Fig. 3 is a side elevation of the stocking 30 after the same has been reenforced and the openings closed.

Fig. 4 is a side elevation of a sock or child's stocking corresponding to Fig. 1.

In carrying out the invention the stocking, as seen in Fig. 1, or the sock or short stocking, as seen in Fig. 4, is woven with the 35 openings 7 across the toe and heel thereof.

The stocking or sock is then reenforced 40 along each edge of each opening 7. This is accomplished by stitching, as at 8, the material, with several lines of stitches substantially parallel with the edge of the opening, and the stitching may be done on a sewing 45 machine, inasmuch as the opening enables the portion of the article at one side of the opening to be folded or turned back while the opposite portion is being stitched. The openings thus give access to the inner surface of the article in order that the stitching 50 may be done conveniently on a sewing machine. Zig-zag or staggered stitching is employed, with the bias stitches extending across the threads of the material, as seen in Fig.

3, thereby tying the threads together, as well as increasing the thickness of the material, in order to resist wear and tear.

After the portions of the stocking or sock along the edges of the openings have been stitched or reenforced, the edges of the openings are secured together by suitable seams, as at 9, thereby closing the openings.

The completed article will thus be reenforced at the toe and heel, and will have a longer life than the ordinary stocking or 65 sock.

The reenforcement may be used at one or more points of the article, and the reenforcement may also be used for all kinds of hosiery.

The reenforced article of hosiery is intended 70 as an article of manufacture, to be produced at the factory or shop, and manufacture is facilitated by the method above described.

Having thus described the invention, what 75 is claimed as new is:—

1. The method of producing a reenforced article of hosiery consisting in first completing the article with an opening at a point where a hole usually occurs, then applying reenforcement to the article along the opposite edges of the opening, and then securing the edges of the opening together to close the opening.

2. The method of producing an article of 85 hosiery consisting in completing the article with an opening across a point thereof where a hole usually occurs, stitching the article along the opposite edges of the opening, and then securing the edges of the opening together to 90 close the opening.

3. The method of producing an article of hosiery consisting in completing the article with an opening across a point thereof where a hole usually occurs, stitching the article 95 with zig-zag stitches along parallel lines at opposite sides of and along the edges of said opening, and then securing the edges of the opening together to close the opening.

4. The method of making an article of 100 hosiery consisting in first making the article with openings at the heel and toe, reenforcing the heel and toe by bias stitching along the edges of the openings, and then closing the 105 openings.

In testimony whereof I hereunto affix my signature.

LOUIS KAPLAN.
